UNITED STATES PATENT OFFICE.

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA.

MOLDING MACHINE.

Application filed January 16, 1922. Serial No. 529,779.

To all whom it may concern:

Be it known that I, WILFRED LEWIS, a citizen of the United States, residing at Haverford, Montgomery County, Pennsylvania, have invented a new and useful Improvement in Molding Machines, of which the following is a specification.

The present invention relates to improvements in the machine shown, described and 10 claimed in Letters Patent of the United States, No. 1,245,114, granted to the same Wilfred Lewis and John T. Ramsden, October 30th, 1917, and its principal object is to simplify the construction by the elimination 15 of parts and to provide for the accomplishment of better results with fewer parts, utilizing certain of the parts for the performance of additional functions and providing simple mechanism for controlling 20 their action as will hereinafter more fully appear.

The invention will be claimed at the end hereof but will be first described in connection with the embodiment of it chosen from 25 among other embodiments for the sake of illustration in the accompanying drawings forming part hereof and in which—

Figure 1 is a side view of so much and 30 of such parts of a machine of the type shown in said patent as are necessary for an understanding of the invention.

Figs. 2 and 3 are side views, partly in 35 section, illustrating features of the invention and showing the parts in two positions and in Fig. 3 the fixed part or housing of the machine H, to which the guide rods 2 are firmly attached as at a, is shown at a lower level than in Fig. 2, in order to illustrate the raised position of the sliding 40 frame.

Fig. 4 is a plan view of the upper part 45 of the mechanism shown at the right hand side in Fig. 2, and Fig. 5 is an enlarged sectional elevation of a loaded check valve thru which the air from the pattern drawing cylinder passes to exhaust as indicated in Figs. 2 and 3.

In the drawings 1 is a frame arranged to slide vertically on the fixed standards 2, for 50 example, in respect to the housing H. 3 are rollover arms that are pivoted to the sliding frame 1 as at 4. 5 is a shockless jarring mechanism and it is arranged at one side of the frame 1. On the other side 55 of the frame 1 is arranged a flask support

6. This flask support is designed to receive and level the mold and the check valve, detailed in Fig. 5, by trapping air at a predetermined pressure in the pattern drawing cylinder. 23 serves to carry the weight 60 of the sliding frame with the roll over frame in pattern drawing position, as will presently appear. In use, when the arms 3 are in the position shown, they are detached from the pattern plate 7 and from 65 the flask which is superposed upon the pattern plate. The mold is then rammed by the mechanism 5 and thereafter the arms 3 are connected with the pattern plate and the frame 1 is lifted and held at rest while 70 the flask is clamped to the pattern plate. Then the arms are turned over, the mold is deposited on the flask support 6, held firmly in position by leveling wedges and unclamped from the pattern plate. 75

But, before unclamping, care must be taken to support the sliding frame, 1, with its roll over-arms and pattern-plate attached, so that there may be as little change 80 as possible in the distribution of weight tending to roll the mold or spring the supporting mechanism when the flask is unclamped from the pattern plate to draw the pattern.

Now, after lifting the mold from the 85 jarring table and rolling it over, valve lever 11 is turned to exhaust from cylinder 23, and the air from this cylinder passes thru the pipe 30 under the check valve 31 loaded by the spring 32 so that the balancing pressure within the cylinder may not fall below that required to support the dead weight of the sliding frame. The unbalanced weight, coming down upon the mold support 6, will, therefore, be substantially 90 no more nor less than the weight of the mold itself, whatever that may be, and when unclamped from the pattern plate, there will be no elastic reactions because there will be no change in the distribution of the total load raised and lowered by the pattern drawing cylinder. Having thus set the mold in position, the frame 1 is again lifted so that the arms 3 draw the pattern. The frame is lifted by the cylinder 23 acting thru bell crank, 19 and link 15, and the rollover arms are turned in respect to the frame 1 by the piston and cylinder 8 acting on the arm 3^a forming part of the rollover arms 3. 100 105 110

According to the application there is but one cylinder, 23, employed to raise and lower the sliding frame. This acts after jarring, to lift the mold a short distance, 5 sufficient to release the stop, 13, so that the handle, 12, may be turned to roll over, after which, valve handle, 11, is turned to exhaust and the mold is lowered on to the support, 6, set to receive it by the ratchet segment 10 as indicated, or by other equivalent means. To obtain the full pattern draft it is important that the support 6, should meet the descending mold just before the sliding frame comes to the end of its downward 15 movement, provision for which is made by said ratchet adjustment. It is also necessary when the pattern has been drawn and the arms 3 rolled back over the jarring table to drop the pattern plate upon said 20 table and to lower the arms, 3, a short distance further, to avoid contact in jarring. But the pressure bottled up in cylinder 23 by the check valve, 31, would not permit this movement of the sliding frame and 25 must be released, provision for which is made by the lever, 37, pivoted at, 38, to the check valve body and designed to lift the stem, 39, against the load-spring, 32, thus allowing the check valve, 31, to open 30 freely and pass the air trapped in cylinder, 23, thru the exhaust passage, 40. This release of pressure is accomplished automatically by the roll over mechanism, as, for example, by the pin or lug, 41, attached to 35 the end of the link, 33, so as to meet the valve lever, 37, just before the crank, 34, meets its stop position. This insures a limited movement of the valve lever, 37, sufficient to permit the check valve, 31, to 40 open as the rollover arms come into position over the jarring table, and, it also guards against any downward movement of the sliding frame, 1, until the rolling movement has been completed, thus causing the 45 pattern plate 7 to meet the jarring table parallel to the latter surface, and giving time to blow off sand if any lodges on the jarring table under the pattern plate.

According to the present invention there 50 is a single piston and cylinder 23 operative to raise and lower the sliding frame, with a dwell between these movements. In the upward movement the flask is lifted from the mechanism 5 and in the second upward 55 movement the pattern is drawn while the flask is on the support 6. There is also a second piston and cylinder 8 operative during the dwell between the upward and downward movements of the sliding frame. 60 There is also valve locking gear responsive to the movement of the frame 1 and operative to compel the operation of the pistons and cylinders in the order named so that the flask will be first lifted, parallel to itself, 65 from the part 5, before it is rolled over

onto the support 6, and then the pattern drawn. A description will now be given of the valve locking gear. The valve 11 is turned in one direction to operate the shockless jarring mechanism 5 and in the other direction to lift the frame 1 through the intervention of the piston and cylinder 23. The valve 12 is turned in one direction to control the vibrator, as for example to engage the notch 12^a and in the other direction to roll the arms 3 over through the intervention of the piston and cylinder 8. As has been said it is important that the valve 11 be operated ahead of the valve 12 in order to lift the frame 1 and the flask 80 and mold carried by the arms 7 from the part 5 before the arms are rolled over. For this purpose the lock 13, Fig. 4, is provided. In Fig. 2 the lock 13 is shown as in position to prevent the handle of the valve 12 from being turned into the position which brings about the rolling over of the arms 3. The lock 13 is carried by a rod 14 having yielding or spring connection with one arm 15 of a bell crank lever, the other arm 16 of which is controlled by a projection 17 carried by a fixed portion of the machine, housing H. The bell crank lever and valves and rod 14 are carried by or connected with the sliding frame of the machine. When the movable frame is in its lowest position, as shown in Fig. 2, the valve 12 is locked and the arms 3 are in the position shown in Fig. 1, so that it is impossible to actuate the valve 12 to roll over the arms, but when the valve 11 has been actuated to lift the frame 1 sufficiently to raise the arms 3 and mold or flask from the part 5, then the bell crank lever assumes the position shown in Fig. 3 in which the lock 13 is withdrawn clear of the valve 12 which may now be actuated to roll over the arms 3 and deposit the flask on the support 6. Then the valve 11 can be further actuated to lift the frame 1 and arms 3 and draw the pattern.

From the foregoing description it will be evident that the piston and cylinder 23 do the work of both balancing and actuating thus simplifying the construction, and it will also be evident that this result is dependent upon valve locking gear of substantially the character described, and also upon the introduction of a loaded check valve to trap air at a predetermined pressure when lowering the mold onto its leveling support and automatic mechanism to release this pressure when lowering the pattern plate onto the jarring table.

It will be obvious to those skilled in the art to which the invention relates that modifications may be made in details of construction and arrangement without departing from the spirit of the invention which is not limited as to those matters or otherwise than

as the prior art and the appended claims may require.

I claim:

1. In a molding machine the combination 5 of a piston and cylinder operative to make its stroke in two movements with a dwell between them, a second piston and cylinder operative during the dwell, valve locking gear responsive to the movement of a sliding frame and operative to compel the operation of said pistons and cylinders in the order named, a sliding frame having rollover arms, connections for causing the first mentioned piston and cylinder in each of its 10 movements to lift the frame and arms, and connections for causing the second mentioned piston and cylinder to roll the arms over.
2. In a molding machine the combination 20 of a sliding frame, rollover arms, actuating mechanism for said parts, a valve for controlling the actuating mechanism to lift the frame, a valve for controlling the actuating mechanism to turn the arms, a lock for the 25 last mentioned valve, and a projection on the frame for releasing the lock when the frame is lifted.

3. In a molding machine the combination of a sliding frame, a flask-support, roll-over 30 arms for depositing a flask on the support by lowering the frame, a piston and cylinder for lowering the frame by exhaust, and a

loaded check-valve for trapping air in the cylinder to balance the weight of the frame and arms, substantially as described.

35

4. In a molding machine the combination of a sliding frame, jar ramming mechanism on one side of the frame, a flask support on the other side of the frame, roll-over arms pivoted to the frame and adapted to deposit 40 a flask on the support and a pattern plate on the jar-ramming mechanism, a piston and cylinder for lowering the frame by exhaust, a loaded check valve for controlling the cylinder-exhaust to trap air, and provisions 45 for automatically releasing the check-valve to permit the arms to descend below the level of the pattern plate when deposited on the jar-ramming mechanism.

45

5. In a molding machine the combination 50 of a sliding frame, jar-ramming mechanism on one side thereof, a flask support on the other side thereof, roll-over arms pivoted to said frame, a roll-over piston and cylinder for the arms, a single piston and cylinder 55 for pressure raising and exhaust lowering the frame, a loaded check valve for the exhaust to balance the frame in pattern drawing position, means for automatically releasing the check-valve in jarring position and 60 mechanical interlock valve gear to compel raising of the frame prior to roll-over of the arms.
